UNITED STATES PATENT OFFICE.

JOHN R. HILSTAD, OF WHITTIER, CALIFORNIA, ASSIGNOR OF ONE-THIRD TO HARRY H. CANTERBURY AND TWO-THIRDS TO GEORGE G. GRIFFITH, BOTH OF WHITTIER, CALIFORNIA.

PORTABLE POWER-OPERATED HAMMER.

Application filed May 9, 1927. Serial No. 189,932.

My invention relates to portable power operated hammers of the character embodied in my co-pending application Serial No. 40,964, filed July 1, 1925, which is capable of being manually moved over sheet metal work such as motor vehicle bodies and fenders and which operates to remove from the metal undulations of any configuration to restore the metal to its original form.

10 It is a purpose of my present invention to provide a power operated hammer having a different and superior means by which the intensity of the hammering action in respect to the work can be manually controlled in a 15 manner to produce intermittent blows of any desired intensity, so that the most delicate hammering of sheet metal or the most severe can be effected at the will of the operator.

It is also a purpose of my invention to provide a power operated hammer in which the hammer element thereof is active to produce a hammering action only when the element is pressed into engagement with the work, the element being normally inactive and becoming inactive immediately upon removal thereof from the work, thus greatly reducing wear of the element and the adjacent parts of the hammer but permanently relieving the hand of the operator from the vibratory action of 30 the hammer when the element is not in actual use.

A further purpose of my invention is the provision in a power operated hammer of means to permit the hammering element to be 35 projected from its casing sufficiently to free itself from the actuating mechanism rather than restrain the element to the extent of destroying the casing and probable injury to the operator when the element for any reason is 40 thrown beyond its normal inward stroke.

I will describe only one form of portable power operated hammer embodying my invention, and will then point out the novel features thereof in claims.

45 In the accompanying drawings,

Figure 1 is a view showing in vertical longitudinal section one form of hammer embodying my invention;

Figures 2 and 3 are sectional views taken on 50 the lines 2-2 and 3-3, respectively, of Figure 1;

Figure 4 is a fragmentary sectional view taken on the line 4-4 of Figure 2;

Figures 5 and 6 are sectional views taken on the lines 5-5 and 6-6, respectively, of Figure 1.

Referring specifically to the drawings, my invention, in its present embodiment, is shown as comprising a casing 15 of tubular form, to which is secured between its ends a 60 tubular handle 16 adapted to be gripped in moving the hammer as a unit over a piece of work. Mounted for reciprocating movement within the casing 15 is a hammer element designated generally at E and comprising a 65 shank 17 of one diameter, on the lower end of which is formed a head 18. On the upper end of the shank 17 is a body 19 constructed to provide a right-angled shoulder or abutment 20 on the lower face of which a cam 21 is 70 adapted to ride. The upper portion of the shank 17 is cut out to accommodate the cam 21 in the reciprocating movement of the hammer element. Above the body 19 the hammer element is provided with a shank 22 slightly 75 reduced in diameter in respect to the body and provided at its upper end with a reduced portion 23 terminating in a head 24. These elements work in a cap 25 removably fitted on the upper end of the casing 15 and secured 80 against displacement by means of a pin 26 engaged by a resilient arm 27 secured by a screw 28 to the casing. This arm 27 is bendable outwardly to disengage the pin 26 and thereby 85 permit removal of the cap. The upper end of the cap is formed with an inturned lip 25a provided for the purpose of retaining thereon a closure disk 29 provided with a vent 90 opening 30. This disk may be formed of metal or any other suitable material capable of being readily fractured to allow the projection of the upper end of the hammer element through the top of the cap 25. Should the hammer element for any reason be projected in its upward stroke above its normal 95 extreme elevated position, the disk 29 will yield to permit the projection of the head 24 therethrough rather than confine the hammer element within the cap and thus injure the cap. It will be understood that the disk 29 100 can be readily replaced with a new one should it become fractured.

To retain the hammer element against accidental displacement from the casing and yet permit of the required reciprocating movement thereof, a washer 31 is mounted on the 5 reduced portion 23 of the hammer element so as to abut a shoulder 32 provided at the junction of the cap and casing and to thus define the lowermost position of the hammer element. This washer 31 is of such internal diameter as to readily pass over the head 24, but it is locked against displacement by means of a U-shaped key 33 applied to the reduced portion 23 so as to be interposed between the head 24 and the washer 31. This key can be 10 readily removed to permit subsequent removal of the washer 31 by first removing the cap 25.

On the lower end of the casing 15 is threaded a collar 34, and on the outer surface of the 20 collar at diametrically opposed points are two pockets 34^a (Figure 6). These pockets receive balls 36 which work in vertical grooves 37 of a cup-shaped anvil 38. The lower ends of the grooves 37 communicate with an annular groove 39, formed in the anvil 38, the grooves 37 functioning as entrances for the balls so that the latter will be finally received in the groove 39 and thereby permit a 90° 25 movement of the anvil to displace the balls from the vertical grooves 37 and thereby secure the balls against displacement. A pair of ears 40 are formed on the casing 15, and secured between these ears by means of a cotter pin 41 is a locking pin 42 which extends 30 downwardly within one of the grooves 37, thereby locking the anvil 38 against rotative movement on the collar 34.

From the foregoing described mounting of the anvil 38, it will be clear that the anvil is 40 capable of vertical movement on the casing 15 in order that it may respond to various adjustments in stroke of the hammer element E, as will be described hereinafter.

Within the casing 15 and surrounding the 45 shank 17 is a cup-shaped housing 43 for a coiled expansible spring 44 interposed between the housing and the hammer head 18. The housing is provided with a radially extending lug 45 movable in a slot 46 of the casing and engageable by one end of a lever 47 fulcrumed on ears 48 formed on the handle 16 at the points indicated at 49. The opposite end of the lever 47 is curved in the form of a trigger to facilitate operation of the lever 55 by the index finger of the hand when the latter is gripped about the handle 16. Operation of the lever 47 depresses the lug 45 and, hence, the housing 43 to compress the spring 44 and thus increase its normal tension. In 60 this manner the intensity of the blows produced by the hammer element can be increased from a minimum as will be hereinafter described.

The cam 21 is formed on one end of a shaft 65 journaled in ball bearings 51 and 52 fitted

in the handle, as shown in Figure 1, with the shaft provided with flanges 53 to secure the shaft against longitudinal displacement. The rear end of the handle 16 is constructed to accommodate a pinion 54 keyed to the shaft 50 and constantly meshing with a smaller pinion 55 secured to or formed integral with the inner end of a stub shaft 56. A cover plate 57 is removably secured to the free end of the handle 16 and this cover plate is provided with a tubular extension 58 containing liners 59 in which the stub shaft 56 is journaled. The stub shaft is provided with a pocket 60 in which is adapted to be received a flexible shaft (not shown) driven by a motor or other suitable means for rotating the stub shaft 56 and thereby effecting a driving of the shaft 50 through the intermediate pinions 54 and 55. Pins 61 project into the pocket 60 and may provide an operative connection between the stub shaft and the flexible shaft inserted into the pocket.

The handle 16 is provided with a screw plug 62 which, when removed, will permit the injection into the handle of a suitable lubricant. The handle is completely filled with the lubricant so that it will be distributed to the bearings 51 and 52, as well as to the pinions 54 and 55, it being noted that the pinion 54 is constructed with openings 54^a to allow the free passage of the lubricant therethrough and through a duct 63 for lubrication of the stub shaft 56. The hammer element E and its correlated parts will be lubricated through the passage of lubricant through the forward ball bearing 51. As clearly shown in Figure 2, the upper edge of the anvil 38 is formed with an annular bead 64 which engages the lower end of a rod 65 movable in a bracket 66 on the casing 15. This rod extends upwardly and into the casing through a suitable opening 66^a where its upper end engages the lower end of a latching pawl 67 pivoted on a pin 68 and engaged by a spring 69, so that it will be yieldably urged inwardly to the solid line position shown. In this position of the pawl, it engages the shoulder or abutment 20 in order to hold the hammer element in an elevated or retracted position, and thus render the cam 21 ineffective to reciprocate the hammer element. However, by moving the anvil 38 upwardly to the dotted line position shown in Figure 2, an upward movement of the rod 65 is effected to force the pawl 67 to the dotted line position in which it is out of engagement with the shoulder 20, thereby permitting the cam to effect the reciprocation of the hammer element.

The operation of the hammer is as follows: With the pawl 67 engaging the shoulder 20, the cam 21, in its rotative movement by actuation of the shaft 50, does not engage the shoulder 20 and, hence, the hammer element remains at a standstill. Upon applying the hammer to the work, the anvil 38 will be

5 moved upwardly on the casing 15, thereby moving the pawl 67 free of the shoulder 20 and thereby allowing the hammer element to respond to the action of the spring 44. As soon as the hammer element is lowered, the cam, in its rotative movement, operates to elevate the element, and under the continued lowering of the hammer element by the spring and its subsequent elevation by the cam, a 10 reciprocating motion is imparted to the hammer element to cause an intermittent tapping of the head 18 against the anvil 38, thereby producing a hammering action upon the work. The construction of the cam 21 is 15 such that, in its rotative movement it suddenly releases the hammer element following elevation thereof, so as to allow the spring 44, in its expansive movement, to project the element downwardly to produce the hammering action. The intensity of this hammering action can be varied at will through actuation of the lever 47. In the normal position of the lever the housing 43 occupies its uppermost position, in which the spring 44 is completely 20 expanded. However, upon actuation of the lever, the housing is moved downwardly, thereby increasing the normal tension of the spring and, as a consequence, increasing its expansive action on the hammer element 25 when released by the cam 21. In this manner, the intensity of the hammering action of the element is increased, and it will be understood that the degree of increase can be varied in accordance with the downward adjustment 30 of the housing 43. Upon release of the lever 47, the housing 43 is free to return to its normal elevated position under the action of the spring 44, so that the hammering element will operate with its normal hammering intensity.

40 As soon as the anvil is removed from the work, it returns to its lowermost position, thereby releasing the rod 65 and permitting the pawl 67 under the action of the spring 69 to return to its normal position in which it 45 engages the shoulder 20 and thereby hold the hammering element against reciprocation. Thus, the hammering element is active only when the anvil is in actual engagement with the work. Obviously, this mode of operation 50 greatly reduces wear of the hammering element and adjacent parts, and the amount of vibration to which the hand is subjected when the hammering element is actually reciprocating.

55 By reference to Figures 1 and 2, it will be noted that the working surface of the anvil 38 indicated at 38^a is of convex form, while the lower edge of the anvil is rounded as indicated at 38^b. By constructing the anvil in 60 this manner, it is possible to concentrate the pounding action of the hammer on a particular and relatively small spot on the work, as it will be understood that by the convexity of the surface 38^a the center of such surface 65 alone can be brought into contact with the

work. The rounded edge 38^b permits the anvil to be applied to normally inaccessible parts of a sheet metal surface, the hammer as a unit being positioned with respect to the work so that only the edge 38^b is in contact 70 with the work. In order that the pounding action of the hammer head 18 may be properly transmitted to the work through the anvil the anvil may be somewhat loosely fitted on the collar 34, so as to allow limited lateral 75 movement thereof, and the anvil shifting to this lateral position when applying the edge of the anvil to the work.

80 Although I have herein shown and described only one form of portable power operated hammer embodying my invention, it is to be understood that various changes and modifications may be made therein without departing from the spirit and scope of the appended claims.

85 I claim as my invention:

1. A power operated hammer comprising a reciprocable hammer element, means for actuating the hammer element, an anvil against which the hammer element is adapted to strike, said anvil being adjustable by compressing it against the work being hammered to vary in a limited degree the pounding action of the hammering element, a spring associated with the element to resist its movement 90 in a direction away from the work and to project the element toward the work, and manually operable means for varying the tension of the spring.

100 2. A power operated hammer comprising a hammer element, means for yieldably urging the element to one extreme position, power operated means for moving the element to another extreme position in a manner to place the first means under tension 105 and then suddenly release the element, thereby allowing the first means to act expansively on the element, and means for adjusting the first means to vary its expansive action on the element comprising a housing movable to compress the first means, and a manually operable lever for moving the housing.

110 3. A power operated hammer comprising a hammer element yieldably urged to one extreme position, means for moving the hammer element to another extreme position and releasing the same, means for holding the hammer element in the second mentioned position, and means operable upon application 115 of the hammer element to a piece of work for rendering said holding means ineffective to hold the hammer element.

120 4. A power operated hammer comprising a hammer element yieldably urged to one extreme position, means for moving the hammer element to another extreme position and releasing the same, an anvil against which the hammer element is adapted to strike, said anvil being supported for limited movement,

means normally acting to hold the hammer element in the second extreme position, and means operable by movement of the anvil as when applying the hammer element to a piece 5 of work for operating the element holding means to release the hammer element.

5. A power operated hammer comprising a hammer element yieldably urged to one extreme position, means for moving the hammer element to another extreme position and releasing the same, an anvil against which the hammer element is adapted to strike, said anvil being supported for limited movement, a spring-pressed pawl normally acting to hold 10 the hammer element in the second extreme position, and a rod operable by the anvil for moving the pawl free of the hammer element.

6. A power operated hammer comprising a reciprocable hammer element, means for actuating the element, and a cap for the element having a displaceable portion so positioned as to be struck and displaced from the cap by the hammer element upon movement of the latter beyond a predetermined position.

7. A power operated hammer comprising a reciprocable hammer element, a housing for the element including a cap, and a closure member removably fitted in the cap and so 30 positioned as to be struck and displaced from the cap by the hammer element should the latter move beyond a predetermined position.

8. A power operated hammer, a reciprocable hammering element, a casing therefor, 35 an anvil on the casing, non-friction means for supporting the anvil for movement lengthwise of the casing, and means for locking the anvil to the casing.

9. In a power operated hammer, a reciprocable hammer element having a head, a member mounted and movable on the hammer element, a spring interposed between the member and the head, and manually operable 40 means engaging the member to move the latter whereby the tension of said spring can be increased.

10. A power operated hammer comprising a hammer element, an anvil against which the hammer element is adapted to strike, the 50 anvil being adjustable by pressing it against the work being hammered to vary in a limited degree the pounding action of the hammering element, means associated with the element for resisting its movement in a direction 55 away from the work and normally acting to project the element towards the work, and manually operable means for varying the degree of projecting action of the last means.

11. A power operated hammer comprising 60 a hammer element, means for yieldably urging the element to one extreme position, power operated means for moving the element to another extreme position in a manner to place the first means under tension and then suddenly release the element, thereby

allowing the first means to act expansively on the element, and means for adjusting the first means to vary its expansive action on the element comprising an abutment movable to compress the first means, and a manually operable lever for moving the abutment. 70

12. A power operated hammer as embodied in claim 1 wherein the last means comprises an abutment movable to compress the spring, and a pivoted member for actuating 75 the abutment.

13. A power operated hammer comprising a hammer element, resilient means correlated with the hammer element normally acting to urge the element to one position, means for 80 moving the hammer to another position against the action of the first means, and means for adjusting the first means to vary the degree of urging action thereof against 85 the hammer element, comprising an abutment movable to vary the tension of the resilient means, and a pivoted member for actuating the abutment.

14. A power operated hammer comprising a hammer element, resilient means correlated with the hammer element normally acting to urge the element to one position, means for moving the hammer to another position against the action of the first means, and means for adjusting the first means to 90 vary the degree of urging action thereof against the hammer element, comprising a cup shaped housing receiving a portion of the resilient means and movable to compress the latter, and a lever for actuating the housing. 95

15. In a power operated hammer, a reciprocable hammer element having a head, a cup shaped member receiving and being movable on the element, a spring interposed between the head and member and having a portion 105 thereof received in the latter, and manually operable means engaging the member for moving the latter to thereby vary the tension of said spring.

16. A power operated hammer comprising 110 a hammer element normally urged to one position, means for moving the hammer element to another position and releasing it, an anvil supported for limited movement and against which the hammer element is adapted 115 to strike, means for holding the hammer element in the second mentioned position, and means operable by movement of the anvil as when applying the hammer element to a piece of work for operating the holding 120 means to release the hammer element.

17. A power operated hammer comprising 125 a casing, a hammer element reciprocable in the casing, a coil spring for urging the hammer element to one extreme position, means for moving the hammer element to its other extreme position and then suddenly releasing the element, a cup shaped housing movable in the casing and receiving a portion of the spring, the casing having a slot, and a 130

manually operable lever for actuating the housing to compress the spring, mounted on the casing and having a portion projecting through said slot and bearing against the housing.

18. A power operated hammer comprising a hammer element yieldably urged to one extreme position, means for moving the hammer element to another extreme position and releasing the same, mechanical means for holding the hammer element in the second mentioned position, and means operable upon application of the hammer element to a piece of work for rendering said holding means ineffective to hold the hammer element.

JOHN R. HILSTAD.
